CLIFFORD E. WENTZEL, OF CINCINNATI, OHIO, ASSIGNOR TO THE BAHMANN IRON WORKS COMPANY, OF CINCINNATI, OHIO, A CORPORATION OF OHIO.

CLOSURE FOR PRESSURE-CHAMBERS.

1,194,798.

Specification of Letters Patent. Patented Aug. 15, 1916.

Application filed March 6, 1915. Serial No. 12,677.

To all whom it may concern:

Be it known that I, CLIFFORD E. WENTZEL, a citizen of the United States, and a resident of Cincinnati, in the county of Hamilton 5 and State of Ohio, have invented certain new and useful Improvements in Closures for Pressure-Chambers, of which the following is a specification.

My invention relates to fluid pressure governing or operating means for machines, such as presses, and especially such as mills for expressing juice from cane, as used in the manufacture of sugar.

The object of my invention is to provide 15 improved construction of devices of this character whereby the pressure chamber is more readily opened for renewing packing means and making other renewals or repairs within said chamber; and which construction 20 at the same time, may be made amply strong to carry the heavy load imposed upon it.

My invention consists in the combination 25 of parts and in the details of construction and arrangement of parts as will hereinafter be more fully described and claimed.

In the drawings: Figure 1 is a side elevation of a cane mill provided with my invention; Fig. 2 is a detail side elevation of the 30 shear bar; Fig. 3 is an end elevation of the same; Fig. 4 is an enlarged sectional view of the top cap on a line corresponding to the line $y-y$ of Fig. 5; and Fig. 5 is an elongated vertical cross section of the top of 35 the cap on the line $x-x$ of Fig. 1.

The cane mill in connection with which I exemplify my invention has the two lower rolls 1 and 2 held positively against horizontal separation by bolts 3 and 4, above and 40 below the bearings of the rolls 1 and 2, and the upper roll 5, which has a journal 6, downward upon which bears the journal box 7 adapted to slide up and down in the upper part 8 of the frame of the machine, and 45 having a pressure plate 9 on its top, with a swivel plate 10 bearing against a concave surface on the top of the pressure plate 9. The lower end of the plunger 11 bears downward or inward against the flat top of this 50 swivel plate 10, and is fitted in the lower or inner end of the bore of the cylinder 12, which cylinder forms an integral part of the top cap 13. This top cap is held down on the top 8 of the frame by upright bolts 14

at opposite sides of the journal 6 and of said 55 cylinder 12.

The lower or inner part of the bore of the cylinder 12 is reduced, forming an annular shoulder 12'. The plunger 11 has a reduced part fitting closely in the reduced part of 60 the cylinder and having around it an annular shoulder 11', above which is a packing 15 of upwardly or outwardly opening U-shaped cross section between said plunger and the walls of the lower or inner end of the main 65 and larger part of the bore of the cylinder. The shoulder 11' rests on the shoulder 12' and relieves the rolls and journal boxes from hydraulic pressure when running idle.

Immediately above the plunger 11, as here 70 shown, is the inlet connection 16 through which fluid pressure, in this example hydraulic pressure, is applied in the device. A resisting plug 17 is closely fitted in the bore of the cylinder 12 with a lower or inner 75 reduced part 18, around which reduced part 18 is another annular packing 19 of downwardly or inwardly opening U-shaped cross section. Thus, if this resisting plug 17 is held in the bore of the cylinder, a pressure 80 chamber 20 is inclosed, with the inlet connection 16 leading into it; and this chamber is made proof against leakage around the plunger 11 and resistance plug 17 by the packings 15 and 19.

Since the packings 15 and 19 must be kept 85 in perfect condition and therefore require renewal or repairs at intervals, it is highly desirable that convenient access to this pressure chamber 20 be possible at any time. In 90 most applications of such devices, as in the present example, access by removal of the plunger involves considerable disassembly of heavy and important parts of the machine on which the device is used, making it desirable to gain access through the head or closure of the cylinder. Owing to the extremely heavy strains which such a device as this must withstand however, it is necessary 95 that the cylinder closing parts be massive, and that any means that fastens them together must be a secure one, while for facilitating the access above alluded to, such fastening means must be capable of ready unfastening.

As shown in the present example, I provide for the above access by making the resisting plug 17 removable from the upper or

outer end of the bore of the cylinder, and provide a secure fastening means by passing a shear bar 21 horizontally through openings 22 in the cylinder walls and through a transverse opening 23 through the resisting plug 17.

A supporting plate 24 is placed over the upper or outer end of the bore of the cylinder 12, and an eye bolt 25 passes loosely through the supporting plate 24 and is screwed into the outer end or top of the resisting plug 17 to project into the transverse opening 23 in said plug and engage with the shear bar 21, which preferably has a depression 26 in its middle to receive the inner end of this eye bolt 25. A nut 27 on the eye bolt 25 bears against the outer side of the supporting plate 24 to hold the resisting plug 17 out toward the outer end of the cylinder.

As herein shown, the shear bar 21 is of substantially rectangular cross section, and the openings 22 in the cylinder walls and the opening 23 in the resisting plug are of corresponding cross section. However, the dimension of each of these openings in the direction of shear is somewhat greater than the corresponding dimension of the shear bar, so that the shear bar fits these openings loosely in this direction except when the eye bolt 25 is screwed in against the shear bar, which will draw the resisting plug upward or outward and bring the inner side of the opening 23 therein out against the inner side of the shear bar where it extends across the bore of the cylinder, and by the bearing of the nut 27 on the outer side of the supporting plate 24 this resisting plug 17 and shear bar 21 are drawn out so that the outer sides of the shear bar bear outward against the outer sides of the openings 22 in the cylinder walls; where the end parts of the shear bar extend laterally therethrough. With the end of the eye bolt 25 bearing in the depression 26 in the middle of the outer side of the shear bar, this shear bar will be held against endwise displacement laterally from the resisting plug and cylinder walls. With this arrangement, which is extremely simple, all of the parts may be made amply massive and strong to resist the strains imposed upon them. At the same time, if it be required to remove the resisting plug 17 from the cylinder 12, it is necessary only to loosen the nut 27 and screw the eye bolt 25 upward in the resisting plug 17, which will allow the resisting plug 17 to drop down somewhat, bringing the bottom of this opening 23 down and thus allowing the shear bar 21 to drop down from the upper sides of the openings 22 in the cylinder walls, and disengaging the lower end of the eye bolt 25 from the depression 26. Thus the shear bar 21 is readily pushed endwise from its position far enough to have its end part seized

in such a manner that it may be readily withdrawn completely from the cylinder walls and resisting plug. This is especially advantageous if the bar has become indented or bent, under the heavy outward pressure of the resistance plug on its inner or lower side. Then suitable lifting means may be engaged in the eye of the eye bolt 25 and the resisting plug along with the supporting plate 24 may thus be withdrawn from the cylinder, giving access to the packings 15 and 19 and to the upper end of the plunger 11, as well as to the lower end of said resisting plug 17; and of course the plunger 11 may be reached and completely withdrawn from the cylinder if required.

If extensive work is to be done on either the plunger or the resisting plug, or in renewing the packings 15 and 19, and it be desired to use the mill during this time, suitable blocking means may be inserted above the block 7 and the parts 9 and 10 in place of this plunger and plug and the shear bar 21 inserted to hold them down, thus allowing positive operation of the machine during this time, it being understood that such positive operation is permissible, although, for the most safe working of the machine, the governing fluid pressure provided in the pressure chamber is highly necessary.

I prefer to provide the single pin 21 of ample cross section to resist the strain, and to have the eye bolt 25 bear down on this pin, with the advantage that the resisting plug is held firmly upward whether the fluid pressure be present in the chamber 20 or not. However, it will be understood that such variations of my invention may be made as may be desirable under various conditions met with, and that while I have shown and specifically described a preferred construction as an example of the embodiment of my invention, I do not wish to be understood as limiting myself to the example shown, but

What I claim as new and desire to secure by Letters Patent is:

1. In a device of the character described, in combination with a cylinder and plunger in said cylinder, a resisting plug in the cylinder, said plunger and said plug and the walls of the cylinder inclosing a pressure chamber and said chamber having an inlet, and means slidably transversely of the cylinder to engage with said resisting plug and hold it toward said plunger.

2. In a device of the character described, in combination with a cylinder and a plunger in said cylinder, a resisting plug in said cylinder, said plunger and said resisting plug and the walls of the cylinder inclosing a pressure chamber, and said pressure chamber having an inlet, and fastening means slidable through a wall of said cyl-

inder and across and in engagement with said resisting plug to hold the plug toward said plunger.

3. In a device of the character described, 5 in combination with a cylinder and a plunger in said cylinder, a resisting plug in said cylinder, said plunger and said resisting plug and the walls of the cylinder inclosing a pressure chamber, and said pressure 10 chamber having an inlet, and a shear bar engaging with a wall of said cylinder and in engagement with said resisting plug to hold the plug toward said plunger.

4. In a device of the character described, in 15 combination with a fixed cylinder and a plunger in said cylinder, a resisting plug in said cylinder, said plunger and said resisting plug and the walls of the cylinder inclosing a pressure chamber, and said pressure 20 chamber having an inlet, and fastening means slideable transversely of said cylinder, and across and in engagement with said resisting plug to hold the plug toward said plunger.

25 5. In a device of the character described, in combination with a fixed cylinder and a plunger in said cylinder, a resisting plug in said cylinder, said plunger and said resisting plug and the walls of the cylinder inclosing a pressure chamber, and said pressure 30 chamber having an inlet, and a shear bar slideable transversely through a wall of said cylinder from its exterior, and across and in engagement with said resisting plug to hold the plug toward said plunger.

6. In a device of the character described, 40 in combination with a cylinder and a plunger in said cylinder, a resisting plug in said cylinder, said plunger and said resisting plug and the walls of the cylinder inclosing a pressure chamber, and said pressure chamber having an inlet, and an imperforate shear bar engaging with a wall of said cylinder and in engagement with said resisting 45 plug to hold the plug toward said plunger.

7. In a device of the character described, 50 in combination with a fixed cylinder and a plunger in said cylinder, a resisting plug in said cylinder, said plunger and said resisting plug and the walls of the cylinder inclosing a pressure chamber, and said pressure chamber having an inlet, and an imperforate shear bar slideable transversely through a wall of said cylinder from its exterior and across and in engagement with 55 said resisting plug to hold the plug toward said plunger.

8. In a device of the character described, 60 in combination with a cylinder and a plunger in said cylinder, a resisting plug in the cylinder, said plunger and said plug and the walls of the cylinder inclosing a pressure chamber, and said pressure chamber having an inlet, means slideable transversely 65 of the cylinder to engage with said resist-

ing plug and hold it toward said plunger, and means engaging with said resisting plug to hold it against said slideable means.

9. In a device of the character described, 70 in combination with a cylinder and a plunger in said cylinder, a resisting plug in the cylinder, said plunger and said plug and the walls of the cylinder inclosing a pressure chamber, and said pressure chamber having an inlet, means slideable transversely of the 75 cylinder to engage with said resisting plug and hold it toward said plunger, and means engaging with said resisting plug to hold it against said slideable means, and engaging against said slideable means to prevent sliding 80 of the means away from its position across said resisting plug.

10. In a device of the character described, 85 in combination with a cylinder and a plunger therein, a resisting plug in said cylinder, said plunger and said resisting plug and the walls of the cylinder inclosing a pressure chamber, and said cylinder having an inlet to said pressure chamber, fastening means 90 slideable through one of the walls of said cylinder and across and in engagement with said resisting plug to hold the plug toward said plunger, and means holding said resisting plug against said fastening means independently of the pressure in the pressure 95 chamber.

11. In a device of the character described, 100 in combination with a cylinder and a plunger therein, a resisting plug in said cylinder, said plunger and said resisting plug and the walls of the cylinder inclosing a pressure chamber, and said cylinder having an inlet to said pressure chamber, fastening means slideable through one of the walls of 105 said cylinder and across and in engagement with said resisting plug to hold the plug toward said plunger, and means holding said resisting plug against said fastening means independently of the pressure in the pressure chamber, said means engaging 110 against said fastening means to prevent said fastening means from sliding from said cylinder and from across said resisting plug.

12. In a device of the character described, 115 in combination with a cylinder and a plunger therein, a resisting plug in said cylinder inclosing between it and said plunger and the walls of the cylinder a pressure chamber, said cylinder having a fluid pressure inlet to said pressure chamber, a shear bar 120 engaging with the walls of the cylinder and extending across and engaging with said resisting plug to hold it toward said plunger, supporting means at the outer end of the cylinder, and a tension element engaging 125 with the supporting means and said resisting plug.

13. In a device of the character described, 130 in combination with a cylinder and a plunger therein, a resisting plug in said cylinder

inclosing between it and said plunger and the walls of the cylinder a pressure chamber, said cylinder having a fluid pressure inlet to said pressure chamber, a shear bar 5 engaging with the walls of the cylinder and extending across and engaging with said resisting plug to hold it toward said plunger, supporting means across the outer end of the cylinder, and tension means engaging 10 with said supporting means and with said resisting plug, and comprising means for engagement to lift said resisting plug and the supporting means outwardly of said cylinder when said shear bar is removed from 15 the above described position.

14. In a device of the character described, in combination with a cylinder and a plunger therein, a resisting plug in said cylinder inclosing between it and said plunger and 20 the walls of the cylinder a pressure chamber, said cylinder having a fluid pressure inlet to said pressure chamber, a shear bar engaging with the walls of the cylinder and extending across and engaging with said resisting plug to hold it toward said plunger, and means engaging with the outer end of the cylinder and with said resisting plug to hold said plug out in the cylinder regardless 25 of the pressure in the pressure chamber, said means engaging with said shear bar to prevent endwise displacement of the bar from the cylinder and resisting plug, the walls of said cylinder at the opposite sides having openings transversely therethrough, 30 and said resisting plug having an opening transversely through it, and said shear bar extending through said openings in said walls and said plug, the dimensions of said openings in said walls and said plug in the 35 direction of shear being greater than the corresponding dimension of said shear bar.

15. In a device of the character described, in combination with a frame, a journal-box movable and guided in said frame, a cap 45 fixed to said frame across said journal-box and having a cylinder therein in fixed relation thereto, with its axis substantially parallel to the direction of guiding of said journal-box, a plunger in said cylinder, and means whereby said plunger resists movement of said journal-box, a resisting plug in said cylinder, said plunger and said resisting plug and the walls of the cylinder inclosing a pressure chamber, and said pressure 50 chamber having an inlet, and means slidably transversely of said cylinder and in engagement with said resisting plug, to hold the plug toward said plunger.

16. In a device of the character described, 60 in combination with a frame, a journal-box movable and guided in said frame, a cap fixed to said frame across said journal-box, and having a cylinder therein in fixed relation thereto with its axis substantially parallel to the direction of guiding of said journal- 65

box, a plunger in said cylinder, and means whereby said plunger resists movement of said journal-box, a resisting plug entirely contained within said cylinder, said plunger and said resisting plug and the walls of the cylinder inclosing a pressure chamber, and said pressure chamber having an inlet, and means slidably transversely of said cylinder and in engagement with said resisting plug, to hold the plug toward said plunger. 70 75

17. In a device of the character described, in combination with a frame, a journal-box movable and guided in said frame, a cap fixed to said frame across said journal-box and having a cylinder integrally formed therein, whereby it is fixed with its axis substantially parallel to the direction of guiding of said journal-box, a plunger in said cylinder, and means whereby said plunger resists movement of said journal-box, a resisting plug in said cylinder, said plunger and said resisting plug and the walls of the cylinder inclosing a pressure chamber, and said pressure chamber having an inlet, and a shear bar slidably transversely through opposite walls of said cylinder from the outside of said cap and through and in engagement with said resisting plug, to hold the plug toward said plunger. 80 85 90 95

18. In a device of the character described, in combination with a cylinder and a plunger therein, a resisting plug in said cylinder inclosing between it and said plunger and the walls of the cylinder a pressure chamber, said cylinder having a fluid pressure inlet to said pressure chamber, a shear bar engaging with the walls of the cylinder and extending across and engaging with said resisting plug to hold it toward said plunger, and means engaging with the outer end of the cylinder and with said resisting plug to hold said plug out in the cylinder regardless of the pressure in the pressure chamber, said means engaging with said shear bar to prevent endwise displacement of the bar from the cylinder and resisting plug, the walls of said cylinder at the opposite sides having openings transversely therethrough, and said resisting plug having an opening transversely through it, and said shear bar extending through said openings in said walls and said plug, the dimensions of said openings in said walls and said plug in the direction of shear being greater than the corresponding dimension of said shear bar, and means supported at the outer end of the cylinder and extending in and engaging with said resisting plug to hold it out in the cylinder with the inner side of its transverse opening against the inner side of the shear bar, and thus hold the shear bar out with its outer sides engaging with the outer sides of 100 105 110 115 120 125 130

the transverse openings in the cylinder walls, said resisting plug and said shear bar being thus held together and the shear bar being thus held in the walls of the cylinder, regardless of the fluid pressure on said resisting plug.

19. In a device of the character described, a cylinder having a bore comprising an outer main part of greater diameter and an inner part of less diameter with an annular shoulder formed therein, a plunger fitting in the part of less diameter with a shoulder to rest on the shoulder in the cylinder, and with a part projecting into the main part of the bore, packing means around this projecting part of the plunger and between this part and the wall of the cylinder, a resisting plug fitting in the outer main part of the bore, said plunger, said plug, and the walls of the cylinder inclosing a pressure chamber, and said pressure chamber having an inlet, and a shear bar extending across the bore of the cylinder and into the walls of the cylinder and engaging across said resisting plug.

20. In a device of the character described, a cylinder having a bore comprising an inner part of less diameter and an outer main part of greater diameter, a plunger fitting in the part of less diameter but projecting into the main part of the bore, packing means around this projecting part of the plunger and between this part and the wall of the cylinder, a resisting plug comprising an outer main part fitting in the outer main part of the bore and having an inner part of less diameter than that of the bore, packing means around this part of less diameter, between it and the walls of the cylinder, and a shear bar extending across the bore of the cylinder and into the walls of the cylinder and engaging across said resisting plug, and means engaging with the outer end of the cylinder and with said resisting plug to hold said plug out in the cylinder regardless of the pressure in the pressure chamber, said means engaging with said shear bar to prevent endwise displacement of the bar from the cylinder and resisting plug, the walls of said cylinder at the opposite sides having openings transversely therethrough, and said resisting plug having an opening transversely through it, and said shear bar extending through said openings in said walls and said plug, the dimensions of said openings in said walls and said plug in the direction of shear being greater than the corresponding dimension of said shear bar, and means supported at the outer end of the cylinder and extending in and engaging with said resisting plug to hold it out in the cylinder with the inner side of its transverse opening against the inner side of the shear bar, and thus hold the shear bar out with its outer sides engaging with the outer sides of the transverse openings in the cylinder walls, said resisting plug and said shear bar being thus held together and the shear bar being thus held in the walls of the cylinder, regardless of the fluid pressure on said resisting plug.
